UNITED STATES PATENT OFFICE.

NICHOLAS MICHALEK, OF ST. JOSEPH, MISSOURI.

CHALK-HOLDER.

1,104,815.

Specification of Letters Patent. Patented July 28, 1914.

Application filed April 6, 1914. Serial No. 830,039.

To all whom it may concern:

Be it known that I, NICHOLAS MICHALEK, a subject of the Emperor of Austria-Hungary, residing at St. Joseph, in the county 5 of Buchanan and State of Missouri, have invented certain new and useful Improvements in Chalk-Holders, of which the following is a specification, reference being had to the accompanying drawings.

10 This invention relates to improvements in chalk holders, and more particularly to that class of chalk holders which are adapted for use in billiard rooms.

An object of this invention is the provision of a chalk holder in which a block of chalk may be securely locked so that the same cannot be removed, whereby the chalk must be entirely worn away by the application of cue tips thereto before another 20 block of chalk can be secured in the holder.

A further object of this invention is the provision of a chalk holder comprising a shell having the opening in one end thereof restricted, and a cap for closing the other 25 end of the shell, a spring being connected to the shell for locking the cap thereon, the spring being held in locking engagement with the cap by the periphery of the block of chalk supported in the shell, so that the 30 cap cannot be removed until the chalk retained in the shell is entirely worn away.

With these and other objects in view, my invention consists in the novel construction, combination, and arrangement of parts, to 35 be hereinafter more fully described, claimed, and illustrated in the accompanying drawing, in which,

Figure 1 is a vertical section of the holder, showing a block of chalk mounted 40 therein; Fig. 2 is a sectional view on the line 2—2 of Fig. 1; Fig. 3 is a vertical section of the holder with the block of chalk removed; Fig. 4 is a vertical section of the shell; and Fig. 5 is a view looking at the 45 open end of the cap of the holder.

Referring more particularly to the drawing, the numeral 1 designates the shell which is designed to encircle a block of chalk 2, the outer edge of the shell being 50 provided with an inwardly extending flange or shoulder 3 which forms a stop for engagement with the chalk to prevent the same from moving out of the shell. A cap 4 is provided for closing the inner end of the shell, the cap being preferably of a length 55 substantially one-half of the length of the

shell 1 and being provided in its periphery with a crimp 5, the crimped portion of the cap being forced inwardly thereof to form an inwardly extending rib 6. The cap 4 is 60 provided with a handle or bail 7 by means of which the holder may be suitably connected to a billiard table or wall. Connected at one end to the inner periphery of the shell adjacent its outer end is a leaf spring 65 8, the inner end of the spring being projected beyond the inner end of the shell, the projecting portion of the spring being bent outwardly to form a latch 9 for engagement with the rib 6 in the cap. 70

In the practical use of my device, the chalk is placed within the shell 1 and pushed downwardly to engage the flange or shoulder 3, the block being provided with a longitudinal groove 10 in its periphery which receives the leaf spring 8. It will be seen from the drawing, that the free end of the spring 8 is curved inwardly to normally dispose the latch 9 thereof out of alinement with the rib 6. The chalk 2, when inserted 80 in the shell, is adapted to force the free end of the spring outwardly to dispose the same in alinement with the rib 6 so that when the cap is placed over the inner end of the shell, the latch of the spring engages 85 the rib 6 thereby locking the cap and shell together. It will be seen that the engagement of the spring 8 within the groove 10 in the block of chalk prevents the chalk from rotating relatively to the shell when a cue tip is applied to the chalk and twisted 90 thereagainst. It will also be readily understood that the inward tension of the spring 8 will prevent the chalk from moving longitudinally of the shell when the chalk has 95 been worn down considerably. After the chalk maintained within the shell has been entirely worn away, it will be seen that the free end of the spring will move inwardly so that the latch portion 9 thereof will move 100 out of engagement with the rib 6 on the cap, whereby the cap may be readily separated from the shell and a new block of chalk may be placed within the shell and the cap replaced thereupon in the same manner. 105

From the above description, taken in connection with the accompanying drawing, it will be seen that I have provided a chalk holder from which accidental disengagement of the chalk is impossible without breaking 110 of the chalk, as the periphery of the block engages the locking spring and maintains

the same in locking engagement with the rib on the cap.

While the accompanying drawing illustrates the shell as cylindrical, it will be readily understood that the shell may be angular in construction to receive an angular block of chalk, the various parts of the device being equally effective regardless of the conformation of the shell.

10 Having thus fully described my invention, what I desire to secure and claim by Letters Patent, is:—

1. A chalk holder comprising a shell having an inwardly extending flange at one end, 15 a cap mounted upon the opposite end of said shell, said cap having an inwardly extending rib formed thereon, a leaf spring connected at one end within said shell, and the opposite end of said spring projecting 20 from the shell for engagement with the rib on said cap, as and for the purpose described.

2. A chalk holder comprising a shell having an inwardly extending flange at its outer 25 end, a cap for engagement with the inner end of said shell to close the same, said cap having an inwardly extending rib formed thereon, a leaf spring connected at one end to the inner periphery of said shell adjacent its outer end, the free end of said 30 spring projecting beyond the inner end of said shell, the free end of said spring being

curved so that the same is normally spaced from the inner periphery of said shell, the projecting portion of said spring being 35 curved to form a latch, the latch being normally disposed out of longitudinal alignment with said rib, said latch being moved inwardly upon application of the chalk within the shell, whereby the latch is securely locked in engagement with the rib on said cap.

3. The combination with a block of chalk having a longitudinal groove in its periphery, of a holder comprising a shell having an inwardly extending flange at one end, said shell being adapted to receive the chalk, a cap for closing the opposite end of said shell, said cap having an inwardly extending rib formed thereon, a leaf spring connected at 50 one end to the inner periphery of said shell adjacent its inner end, the body of said spring engaging the groove in the periphery of said chalk and the opposite end of said spring projecting within said cap for engagement within said rib, as and for the purpose described.

In testimony whereof I hereunto affix my signature in the presence of two witnesses.

NICHOLAS MICHANEK.
